UNITED STATES PATENT OFFICE.

WILLIAM C. FISCHER, OF NEWARK, NEW JERSEY.

SHADE-ROLLER.

1,355,458.

Specification of Letters Patent. Patented Oct. 12, 1920.

Application filed September 13, 1919. Serial No. 323,489.

To all whom it may concern:

Be it known that I, WILLIAM C. FISCHER, a citizen of the United States, residing at Newark, in the county of Essex and State 5 of New Jersey, have invented certain new and useful Improvements in Shade-Rollers, of which the following is a specification.

This invention relates to spring rollers for window shades, and its objects are to 10 cheapen the construction of these devices and render them more durable and efficient.

In the accompanying drawings, fully illustrating the invention,

Figure 1 is a side elevation of the im- 15 proved shade roller;

Figs. 2 and 3 are views showing the barrel of the roller in longitudinal section so as to reveal the internal mechanism at the fixed-trunnion end of the shade roller, Fig. 20 2 showing the spindle projecting and engaged in, and Fig. 3 showing said spindle retracted and withdrawn from, the adjoining shade roller bracket, which also appears in section;

Fig. 4 is an elevation of the end of the 25 shade roller appearing in Figs. 2 and 3, with the pawls and their mounting and cap therefor removed;

Fig. 5 is a longitudinal sectional view of 30 the end of the barrel and said mounting and the cap, the latter being detached;

Fig. 6 is an end elevation, the spindle appearing in section;

Fig. 7 is a plan of said mounting and the 35 pawls;

Fig. 8 is a sectional view of the rotating-trunnion end of the shade roller; and

Fig. 9 shows in elevation, the bracket, appearing in Figs. 2 and 3, with the spindle 40 engaged therein.

In the drawings, *a* is the barrel of the improved shade roller, which I prefer to form of a suitable length of paper or other cheap compressed fibrous tubing cut off to 45 the proper length, said material being light, strong and considerably less expensive than wood ordinarily used. Over one end of this barrel is fitted the usual cap *b* having the rotating spindle *c* adapted to turn in a 50 suitable bracket, not shown. To the other end of the barrel *a* is secured a mounting of well-known form, consisting of a disk *d* having tangs *e* engaged in the end of the barrel and a central bearing opening *f*, the 55 same having pivoted therein the pawls *g*

and also having pawl stops *h*. *i* is an apertured cap which in the usual manner fits over said end of the barrel and more or less covers the mounting *d* and the pawls, it being adapted to be clenched and thus secured to 60 the barrel in any well-known way.

To form the aforesaid spindle I take a length of heavy wire and near one end provide a rebend *j* therein, the portions of the wire being preferably spread apart at a 65 point suitably short of the end of the rebend, as at *k*, to form a shoulder, and more or less near the middle of the length of the wire I bend it back on itself and form a loop *l* of suitable length, with preferably straight 70 sides, the portions *m n* of the wire between such loop and the end portion thereof which has been rebent to form the rebend *j* being straight, parallel with each other, and lying each close to the longitudinal central axis 75 of the loop *l* and rebend *j*. The form of the wire as thus described, is clearly shown in Figs. 2 and 3.

The spindle thus formed has its rebend *j* journaled in the bearing opening *f* of the 80 mounting *d*, said spindle projecting into the barrel and its loop being of such transverse dimension as more or less closely to fit the interior thereof and form a bearing therefor.

o is a torsion spring which is inclosed in the barrel and has one end suitably hooked around the wire of the spindle, as at *p*, and the other end bent off and engaged in a notch *q* (Figs. 4 and 5) at the end of the 90 barrel. The spring normally tends to thrust the spindle outwardly of the barrel, its shoulder *k* by engaging the mounting *d* and shown in Fig. 2 limiting the outward movement. The rebend *j* forms not only the 95 fixed trunnion of the shade roller but the ratchet which coacts with the pawls *g*. See Fig. 6. It will be observed that the spindle may be moved lengthwise, against the tension of the spring, into the barrel (compare 100 Figs. 2 and 3), wherefore, instead of using a bracket with a notch opening at the top thereof and having the disadvantage of permitting the shade roller to be accidentally unshipped therefrom, I may use a bracket 105 *r*, such as is shown in Fig. 9, having a non-circular hole *r'* which is closed on all sides, it being understood that the trunnion formed by the rebend *j* is entered into this hole by pressing back the spindle and then 110

shifting the shade roller until the spindle is alined with the hole, whereupon it will spring into place.

The member forming the parts *j*, *l*, *m*, *n* obviously considerably simplifies the construction of spring shade rollers, the usual expedient comprising several parts to form the fixed-trunnion, the ratchet, a spindle and means to properly center its inner end.

10 Ordinarily, the spring is anchored in some way at its inner end to the barrel and at its outer end to the trunnion; by anchoring the spring at its inner end to the aforesaid member and at its outer end to the barrel there is a further contribution to simplicity of construction, and the assembling and disassembling are rendered more facile.

I do not wish to be limited to the details herein set forth, excepting as indicated in the following which sets forth what I claim.

1. In combination, the barrel having one end portion tubular, a pawl and a mounting therefor on the end of said portion, a spindle extending into said tubular portion and formed of a length of wire having its outer end portion rebent and the rebent part forming the fixed trunnion of the shade roller, said end portion of the wire also having a ratchet to coact with the pawl, and a torsion spring in said end portion of the barrel connected at its end portions to the spindle and barrel.

2. In combination, the barrel having one end portion tubular, a pawl and a mounting therefor on the end of said portion, a spindle extending into said tubular portion and formed of a length of wire having its outer end portion rebent and the rebent part forming the fixed trunnion of the shade roller, and also a ratchet to coact with the pawl, and a torsion spring in said end portion of the barrel connected at its end portions to the spindle and barrel.

3. In combination, the barrel having one end portion tubular, a pawl and a mounting therefor on the end of said portion, a spindle extending into said tubular portion and formed of a length of wire having its inner end portion bent into a loop forming

a bearing and having bearing contact with the interior surface of said tubular end portion of the barrel, the outer end portion of said wire forming the fixed trunnion of the shade roller and also having a ratchet to coact with said pawl, and a torsion spring in said end portion of the barrel connected at its end portions to the spindle and barrel.

4. In combination, the barrel having one end portion tubular, a pawl and a mounting therefor on the end of said portion, a spindle extending into said tubular portion and having a fixed enlarged inner end portion forming a bearing and having bearing contact with the interior surface of said tubular end portion of the barrel, the outer end portion of said spindle forming the fixed trunnion of the shade roller and also having a ratchet to coact with the pawl, and a torsion spring in said end portion of the barrel connected at its end portions to the spindle and barrel.

5. In combination, the barrel having one end portion tubular, a pawl and a mounting therefor on the end of said portion, a spindle having the fixed trunnion of the shade roller and also a ratchet to coact with the pawl and extending into said end portion of the barrel, a torsion spring in said end portion attached at its inner end portion to the spindle, and means to secure the outer end portion of the spring to the outer end of said barrel.

6. In combination, the barrel having one end portion tubular, a pawl and a mounting therefor on the end of said portion, a spindle having the fixed trunnion of the shade roller and also a ratchet to coact with the pawl and extending into said end portion of the barrel, and a torsion spring in said end portion attached at one end portion to the spindle and at the other end portion to the barrel, said spindle being movable in said tubular end portion toward the other end of the barrel and having such movement normally resisted by the spring.

In testimony whereof I affix my signature.

WILLIAM C. FISCHER.
